US00D524071S

(12) **United States Design Patent** (10) **Patent No.:** **US D524,071 S**
(45) **Date of Patent:** **** Jul. 4, 2006**

(54) **CHAIR**

(75) Inventor: **Paul Brooks**, Luton (GB)

(73) Assignee: **Senator International Limited** (GB)

(**) Term: **14 Years**

(21) Appl. No.: **29/217,452**

(22) Filed: **Nov. 16, 2004**

(30) **Foreign Application Priority Data**

May 17, 2004 (EM) 000180294-0003

(51) **LOC (8) Cl.** **06-01**

(52) **U.S. Cl.** **D6/379**

(58) **Field of Classification Search** D6/334,

D6/335, 371-373, 374, 375, 376, 379, 380,

D6/500-502; 297/239, 248, 411.27, 445.1,

297/446.1

See application file for complete search history.
